DESIGN FOR A COMBINED BOTTLE AND DISPENSING STOPPER

Alfred A. Flaster, New York, N. Y.

Application February 19, 1942, Serial No. 105,891

Term of patent 3½ years

To all whom it may concern:

Be it known that I, Alfred A. Flaster, a citizen of the United States of America, residing in New York city, county of New York, and State of New York, have invented a new, original, and ornamental Design for a Combined Bottle and Dispensing Stopper, of which the following is a specification, reference being had to the accompanying drawing, forming part thereof, wherein—

Figure 1 is an elevational view of a combined bottle and dispensing stopper, showing my new design.

Figure 2 is a fragmentary elevational view thereof showing the stopper in an uncorked position.

Figure 3 is a top plan view of the combined bottle and dispensing stopper, as shown in Figure 1.

I claim:

The ornamental design for a combined bottle and dispensing stopper, substantially as shown.

ALFRED A. FLASTER.
